UNITED STATES PATENT OFFICE.

WILLIAM B. DEAN, OF NEW YORK, N. Y.

FRUIT-SQUEEZER.

SPECIFICATION forming part of Letters Patent No. 253,353, dated February 7, 1882.

Application filed May 10, 1881. (Model.)

To all whom it may concern:

Be it known that I, WM. B. DEAN, of the city of New York, county and State of New York, have invented a new and Improved 5 Lemon-Squeezer, of which the following is a full and clear description, reference being had to the accompanying drawings, forming part of this specification.

My invention relates to a lemon-squeezer; 10 and it consists in the combination of parts hereinafter particularly described, and more at length recited in the claims.

Figure 1 is a side elevation of my improved 15 lemon-squeezer, partly in section; and Figs. 2 and 3, modified forms of the same.

In all these illustrations like parts are represented by similar letters of reference.

The construction of my invention as represented by Fig. 1 consists of the holding-frame 20 A, the juice-cup B, the bottom juice-extracting die or strainer, C, and the top juice-extracting die, D, connected with the lever or handle E. Each of these parts involves principles which I consider new and useful.

25 The holding-frame A consists of the ring F, in which rests the juice-cup B.

The handle G is constructed with its bottom part broad and rounded to form an easy grasp for the hand, and reaches back and is connected 30 with the standards H H, which serve to elevate the handle and admit the fingers underneath.

The front standard, I, is necessary when it is desired to avoid having the juice-cup form a front rest or standard, which is preferable 35 with a removable cup. I prefer a removable cup because it can then be made of non-corrosive material—such as glass, wood, rubber, earthenware, &c.—while the frame, which must be strong, can be cast in gray or malleable iron.

40 The cup, however, may be cast with the frame, as shown in Fig. 2, in which the ring F, projecting upward from the bottom of the cup, serves as a rest for the bottom juice-extracting die, the depression J in the ring permitting the juice to pass out into the cup.

45 It is evident that by constructing the frame as above specified in regard to the standards or feet attached to the handle the lemon-squeezer may be placed on a table or other 50 convenient place and a lever force brought to

bear, in which the weight of the body is made to assist in squeezing. I am aware that this feature alone is not new; but the attaching of legs to a handle, thus forming a proper rest, and elevating the handle to admit the fingers underneath, thus enabling the operator, while in the act of pressing downward, to grasp the lower handle and combine both pressure and compression, I consider new. To combine these two powers in a lemon-squeezer is one of the 60 objects sought. I have therefore been explicit in my explanation of this feature of my invention.

At the point K is pivoted the handle E.

The juice-cup B, which I make preferably of 65 glass in an iron mold, is provided with two shoulders, one outside and one inside, the one outside, L, being to rest on the ring F, the one inside, M, being to form a rest for the bottom die, C.

70 N is a lip to facilitate turning the juice from the cup.

The bottom die, C, is made in one piece. It is about three-quarters of an inch in height, with slanted or perpendicular sides, a shoulder, 75 O, being formed on the bottom to rest on the juice-cup. The top is flat, with the outer edge elevated about one-eighth of an inch, this elevation being tapered to a thin edge at the top to form the annular cutting-edge P. The bottom 80 of the die is provided with holes cut in the edge to allow the juice to escape from the cup.

The top die, D, has a flat corrugated surface, the corrugations Q serving to prevent the lemon from slipping backward while in the act 85 of squeezing. This die may be a piece of wood fastened to the lever with screws, as shown in Figs. 1 and 2; or it may be cast with the handle, as shown in Fig. 3.

The superiority which the construction of 90 the lower die has over any other in use consists—

First. In avoiding the resisting force of the rind, thereby requiring less power to squeeze the lemon. The lemon, being cut in halves, is 95 placed, cut side down, on top of the lower die, so that when pressure is exerted the rind passes down outside of said die unresisted, while the pulp, being stripped from the rind by the annular sharp-edged projection O, is forced 100

upward into the top of the rind, receiving the entire force of the pressure—a principle which I consider new and valuable. The pulp and juice are unable to escape on account of the 5 annular projection, except that the juice escapes through perforations in the die into the cup below, and in being turned from the cup is restrained.

Second. It produces pure juice—that is, free 10 from rind-oil, this being evident from the fact that no pressure bears upon the cut edge of the lemon, and the principle of its working is such that it seldom, if ever, breaks the rind elsewhere.

15 The semicircular corrugated depression R may be used as a cork-press. The bottom die, C, may be cast with the handle, as illustrated by Fig. 3. Also, the bottom die may be made removable, irrespective of the cup, by making 20 the ring F of proper size and shaping the bottom part of the die to set within and on the ring, somewhat after the manner shown in Fig. 2; or the frame, as represented in Fig. 1, may be made with the ring small enough to accommodate 25 the die and be elevated on the standards H and I sufficiently to admit a vessel being passed underneath the bottom die to catch the juice, which would be a convenient form of construction and one which I may sometimes adopt.

30 What I claim, and desire to secure by Letters Patent, is—

1. In a lemon-squeezer, the combination, with the upper handle, E, of the lower handle, G, running parallel therewith and having legs or 35 standards H H, secured at its extreme end,

whereby in squeezing a lemon the power of compression by the hand may be combined with pressure exerted upon the upper handle, substantially as shown and described.

2. A lemon or fruit squeezer constructed 40 substantially as herein shown and described, consisting in the combination of the legs I H with the lower handle, G, provided with a frame, A, the juice-cup B, the removable die C, and the hinged handle E, provided with a 45 stationary die, D, as set forth.

3. In a lemon-squeezer, the combination, with the frame A, having ring or shoulder F, of a juice-cup, B, forming part of the squeezer and supporting a perforated die, substantially as 50 herein shown and described, whereby the juice will be caught as it is expressed from the lemon and restrained through the die by inverting the squeezer, as set forth.

4. In a lemon-squeezer, the removable bottom die, C, constructed with a projecting cutting-edge, P, around its top, substantially as 55 herein shown and described, whereby the pulp is collected above the die, as set forth.

5. In a lemon-squeezer, the combination, with 60 the frame A, having ring F, of the juice-cup B, having shoulders L M, and the separate die C, substantially as herein shown and described, whereby the said cup and die are connected with and supported by the said frame, as set 65 forth.

WM. B. DEAN.
